UNITED STATES PATENT OFFICE.

HJALMAR FREDERIK EIKEN, OF SKORPING, DENMARK.

APPLIANCE FOR REGULATING THE HARDNESS OF RÖNTGEN-RAY TUBES.

1,418,139.

Specification of Letters Patent. Patented May 30, 1922.

Application filed January 15, 1920. Serial No. 351,698.

To all whom it may concern:

Be it known that HJALMAR FREDERIK EIKEN, citizen of the Kingdom of Denmark, residing at Nationalforenings Sanatorium, 5 at Skorping, Denmark, has invented certain new and useful Improvements in Appliances for Regulating the Hardness of Röntgen-Ray Tubes, of which the following is a specification.

10 The present invention relates to a device by means of which the hardness of Röntgen-ray tubes may be regulated while the tubes are being used. The penetrative force of Röntgen-rays varies continually and increases with the vacuum in the tube. The 15 vacuum increases with use of the tube, and it, therefore, becomes necessary to provide means for controlling the vacuum so as to regulate the penetrative power of the rays.

20 Various methods and devices for this purpose are known. One of the most commonly known regulating methods is the so-called osmo-regulation by which a thin tube of 25 platinum, palladium or similar metal communicating with the interior of the Röntgen-tube is heated to glow-heat by means of a gas or alcohol-flame. A portion of the hydrogen present in the flame diffuses then through the wall of the tube into the Röntgen-ray tube and softens the latter.

30 This regulation is difficult on account of requiring the presence of a flame, and it is not suited for operation at some distance from the Röntgen-ray tube, a feature which would very frequently be desirable.

The present invention relates to a regulating device which is easy and simple to manipulate at any distance from the Röntgen-ray tube, and by which the use of a flame is 40 avoided. The invention is based on the fact that some metals, especially palladium, allow the diffusion of gases, especially hydrogen, even at ordinary temperature. A thin tube, a plate or the like of such metal is 45 placed in such a manner that it communicates with the interior of the Röntgen-tube and, at the same time, acts as an electrode in an electrolyte by which, when current is sent through, a suitable gas is generated which then diffuses into the Röntgen-tube. The regulation may thus be effected simply by closing the circuit by way 50 of the electrolyte. On the drawing,

55 Fig. 1 shows, diagrammatically, the principle underlying the invention,

Fig. 2 a vertical section of one manner of constructing the regulating device,

Fig. 3 the same, in end view,

Fig. 4 a vertical section of another construction,

60 Fig. 5 this other construction, in end view.

In Fig. 1, 1 indicates an enlargement on the Röntgen-tube whereon the regulating device is to be placed. 2 is a thin tube of suitable metal, for instance palladium. This 65 tube is open at one end 3, extending into the Röntgen-tube into the wall of which the tube 2 is fused. The other end of the tube 2 which is closed, extends into a vessel 5 containing an electrolyte, for instance diluted sulphuric acid. In the vessel there is also provided another electrode 4 which may be of carbon or other suitable material. The electrodes 2 and 4 are connected, by means of conductors 8 and 9, to a battery 70 75 6 and a switch 7. The battery may consist of galvanic elements or of accumulators, or use may be made of the current from a lighting plant, there being inserted a suitable series resistance, for instance a lamp. When 80 the switch 7 which may be any kind of circuit-breaker or push-button is closed, a current will commence to pass through the circuit, whereby the electrolyte is decomposed. The gas generated at the electrode 85 2 diffuses through this tube into the Röntgen-tube, thereby decreasing the vacuum.

In Figs. 2 and 3, there is shown a modification of the device in which the electrolyte-container 5 is provided with a tubular member 10 adapted to receive the tubular enlargement 1 on the Röntgen-tube. The electrode 2, which extends into the electrolyte-container 5, is connected to a binding post 11 to which the conductor 8 may be 90 connected. The other electrode 4 which may be of any shape is connected to a binding post 12 to which the conductor 9 may be connected. The electrolyte-container 95 may be of insulating material or of metal, and in this latter case the binding post 11 should be insulated from the tubular member 10.

100 This construction is especially suitable for use in connection with Röntgen-tubes originally arranged for the ordinary osmo-regulation by which the palladium tube 2 is heated by a flame. When the novel regulating device is to be used, the electrolyte-container 105 is fitted onto the enlargement 1, 110

and the palladium tube is then bent down into the electrolyte-container 5 and is connected to the binding post 11.

Figs. 4 and 5 show another modification 5 of the device, the electrolyte-container being integral with the glass wall of the Röntgen-tube. Into the end wall 13 of the electrolyte-container the electrodes 2 and 4 are fused, so that the conductors 8 and 9 may be 10 soldered to or in any other suitable manner connected to the projecting ends of the electrodes. The electrode 2 is inserted through the other wall 14 of the electrolyte-container which also forms an end wall 15 in the Röntgen-tube. The electrode 2, throughout its entire length or a portion thereof, forms a tube being open at the end 3 which projects into the Röntgen-tube. A tube 15, by way of which the electrolyte may 20 be poured into the electrolyte-container 5, prevents the electrolyte from escaping, even

if the Röntgen-tube might occupy a sloping position. The tube 15 may be closed by means of a plug 16.

As will be obvious other modifications 25 may be made, and those shown may be further modified or altered or have details thereof omitted without departing from the spirit of this invention as defined by the following claim.

Patent claim:

A device for controlling the vacuum in a Röntgen-tube comprising an electrolyte-container having a tubular extension embracing the Röntgen-tube, and an electrode communicating with said tube and extending into said container, the gas liberated from the electrolyte being conducted through said electrode.

In testimony whereof he affixes his signature this 17th day of November, 1919.

HJALMAR FREDERIK EIKEN.
